UNITED STATES PATENT OFFICE

LOUIS COHEN, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

ELECTRICAL SIGNALING

Application filed July 29, 1925. Serial No. 46,831.

This invention relates to a method for the reception of high frequency signals particularly adapted for use in signaling over wires which may be either telephone, telegraph or 5 power lines.

The principal object of my invention is to provide methods and means whereby several messages can be received simultaneously at 10 any point on a line over which the signals are transmitted without interfering with each other.

In the general practice today of the reception of signals, if it is desired to receive more than one signal at any one station, some form 15 of electrical tuning is relied upon to secure selectivity which may be satisfactory if the frequencies of the signals to be received are widely separated. If, however, the frequencies of the signals are not sufficiently 20 wide apart and particularly if more than two messages are to be received at the same point, the tuning methods for obtaining selectivity are not quite adequate. Unless a very complicated network of circuits is employed, 25 and in this case the operation of the system would be quite difficult, a certain degree of interference between the different messages received is always experienced.

In this invention a new principle is introduced 30 securing a higher degree of selectivity and rendering the receiving circuits free from interference. This is accomplished by the use of simple coupled tuned circuits, and also providing additional circuits in which a current flow is set up of exactly the same character as the current of the interfering signal, 35 and coupling this additional circuit to the receiving circuit in such a way as to neutralize any residual interfering effects which cannot be eliminated by the process of tuning. If 40 several signals are to be received at the same point, several additional circuits are provided, each of which is so adjusted that the current flow in each of these separate circuits 45 is of exactly the same character in the matter of frequency and phase, and these several additional circuits are coupled to the receiving circuit and so connected as to induce in the receiving circuit currents in opposite directions to those produced by the various inter- 50

ferring signals, and thereby completely neutralize the interfering effects of these various signals which are to be excluded from the receiving circuit.

Let us assume for the purpose of illustration that two signals of different frequencies f_1 and f_2 are being transmitted simultaneously over the line. At the receiving end of the line two circuits are provided tuned respectively to the two frequencies. A certain amount of current however of the frequency f_2 may find its way into the circuit tuned to the frequency f_1 , and vice versa. Now, to neutralize these interfering currents in the receiving circuit two additional circuits are provided which are connected to the same point on the line and so adjusted that the current flow in these circuits will be of the same character in the matter of phase as the interfering signal of frequency f_2 will have 60 in the circuit tuned to the frequency f_1 , and also as the interfering signal of f_1 will have in its operation in the circuit of f_2 . By coupling these auxiliary circuits to the receiving circuits in such a way as to set up currents 65 in these receiving circuits in opposite direction to that produced by the interfering signals, the interference effects are completely 70 neutralized.

In the accompanying drawings:—

Figure 1 is a schematic drawing showing an arrangement for the reception of two signals of two different frequencies;

Figure 2 is a modification in which an arrangement is shown for the simultaneous reception of three signals of three different frequencies.

In Figure 1, 1 and 2 represent the end of a line over which the high frequency signals are transmitted. A and B are the points on the line at which the receiving system is connected. Reference characters 3 and 4 indicate two condensers which permit the high frequency signal currents to pass but blocking out any low frequency currents which may flow on the line. At the junction point between the two condensers 3 and 4, two tuned receiving circuits are connected, one comprising inductance 6 and condenser 7 connected in series and also connected to ground 100

at the point 8, and the other comprising inductance 16, condenser 17, connected in series, and also connected to ground at the point 8. Each of these two tuned circuits is separately 5 tuned to be in resonance for one of the two frequencies of the two signals which are to be received. Each of these tuned circuits is coupled to a secondary circuit adjusted to be in resonance for the same frequency. The 10 circuit 5, 6, 7, 8, is coupled to the secondary circuit 9, 10, and the circuit 5, 16, 17, 8, is coupled to the secondary circuit 18, 19, 21. At the terminals of the condensers 10 and 19 15 suitable detectors are connected across the line represented at 20. Now it will be assumed that the circuit 5, 6, 7, 8, and the circuit 9, 10, 11, coupled to it, are tuned to a frequency f_1 , and that the circuit 5, 16, 17, 8, and the circuit 18, 19, 21, coupled to it, are 20 tuned to frequency f_2 . The tuning of these two circuits may not be sufficient to separate the two signals completely and a certain amount of current of frequency f_2 may find its way into the circuits tuned to the frequency f_1 and vice versa. To eliminate these 25 interfering effects two additional circuits are provided connected to the point 5, one consisting of inductance 12, capacity 13, and variable resistance 14 connected to ground at 30 a point 8, and the other additional circuit also connected at a point 5 consisting of inductance 22, condenser 23 and variable resistance 24 and connected to ground at 8. The interfering signal of frequency f_2 produces a current flow in the circuit which is tuned to f_1 of a certain amplitude and phase. To neutralize 35 this effect the additional circuit 5, 12, 13, 14, 8, is so adjusted that the current flow of the frequency f_2 in it will have the same 40 phase as it has in the circuit which is tuned to f_1 . This can be accomplished by the proper choice of the inductance 12, the capacity 13, and the variable resistance 14. The amplitude of the current flow is also 45 determined by these electrical constants and further the coupling between 12 and 11 can be varied so as to introduce into the circuit 9, 10, an opposite current of exactly the same magnitude as the interfering current which 50 is induced in the circuit 9, 10, due to the coupling to the circuit 6, 7, 8. In a similar way the additional circuit 22, 23, 24, 8, is adjusted as to neutralize the interfering effect 55 of the signal of frequency f_1 flowing into the circuit 18, 19, 21 which is intended for the reception of the signal of the frequency f_2 .

Figure 2 is a modification of Figure 1 showing an arrangement for the simultaneous reception of three messages characterized by 60 three different frequencies. In this arrangement there are three separately tuned circuits each one of which is associated with a secondary circuit tuned to the same frequency. For each of these tuned circuits 65 two additional circuits are provided and so

adjusted as to neutralize the interfering effects in each one of these circuits which may be produced by the other two signals in exactly the same manner as described above in detail for the system of reception of two signals. At the point 5 is connected the three 70 tuned circuits, one consisting of inductance 6, capacity 7, ground 8, associated with the secondary circuit 11, 9, 10, 26, another tuned circuit consisting of inductance 16, capacity 17 and ground 8, associated with the secondary 75 tuned circuit consisting of 18, 19, 30, 21, and the third tuned circuit consisting of inductance 34, capacity 35 and ground 8, associated with the secondary circuit 39, 37, 36, 45. For each of these circuits auxiliary 80 circuits are provided which are coupled to the secondary circuit and these auxiliary circuits are so adjusted in the matter of amplitude and phase as to neutralize the interfering effects of the two other signals. 85

While I have described my invention in certain particular embodiments I desire that it be understood the modifications may be made without departing from my invention 90 and that I intend no limitations upon the invention other than are imposed by the scope of the appended claims.

What I claim and desire to secure by Letters Patent of the United States is as follows: 95

1. In a system for the simultaneous reception of two high frequency signals of different frequencies transmitted over a line, said system including a line, two tuned circuits 100 adjusted to respond to different frequencies and connected to a point on the line, two secondary circuits separately coupled to the said tuned circuits, each of said two secondary circuits including inductance and capacity, an auxiliary winding in series with 105 said inductance and capacity in each of said secondary circuits, and auxiliary circuits each having an inductance, a capacity and a resistance unit connected in series between a point on the line and the ground, said auxiliary circuits being adjusted in phase by changing the value of said resistance unit, each of said auxiliary circuits being connected by a variable coupling to one of said secondary circuits so as to induce in said secondary 110 circuit currents of the same phase and the same amplitude but in opposite direction to those produced by the interfering signals. 115

2. In a multiplex system for the simultaneous reception of several high frequency signals transmitted over a line comprising a multiplicity of tuned circuits connected to a point on the line, each of said circuits being 120 tuned to an independent frequency, a plurality of secondary circuits each comprising an inductance, a capacity and independent inductances in series, each of said independent inductances being separately coupled to one of a plurality of auxiliary circuits, each of 125 said auxiliary circuits comprising an induc- 130

tance, a capacity and an adjustable resistance unit connected in series and disposed between a point on the line and ground, each of said auxiliary circuits being adjusted in the matter of phase and amplitude to correspond exactly to the character of the current of selected signals transmitted over said line and so related to the secondary circuit with which the particular auxiliary circuit is associated so as to balance out interfering effects of signals other than those selected by the secondary circuit.

3. In a multiplex system for the simultaneous reception of several high frequency signals transmitted over a line, said system comprising a multiplicity of tuned circuits electrostatically coupled to a point on the line, each of said circuits being separately tuned to the different transmission frequencies and coupled to a tuned secondary circuit, said secondary circuit including an inductance, a capacity, and independent coupling coils connected in series with said elements and a plurality of auxiliary circuits each including an adjustable resistance and a connection to ground at one end and to a point on the line at the opposite end, said auxiliary circuits each corresponding to the frequencies transmitted over said line, each of said auxiliary circuits being coupled with one of said independent coupling coils and adjusted to produce therein a current flow of proper phase and amplitude corresponding to a particular interfering signal of one of said frequencies transmitted over said line and so related to the secondary circuit as to eliminate therein the effects of that particular interfering signal.

4. In a multiplex signaling system, a line wire circuit, a plurality of tuned circuits connected to said line wire circuit for receiving different frequencies transmitted over said line wire circuit, a secondary circuit connected with each of said tuned circuits, said secondary circuit including an inductance and tuning capacity and a plurality of independent inductances corresponding in number to the number of signaling frequencies transmitted over said line wire circuit, an auxiliary circuit including adjustable resistance, capacity and inductance connected between a point in said line wire circuit and the ground and individually coupled with a selected one of the independent inductances in each of said secondary circuits, said adjustable resistance in each of said auxiliary circuits operating to control the phase relation of the currents in said independent inductances and in the corresponding secondary circuit whereby interfering currents in said secondary circuits of a frequency remote from the frequency for which the corresponding secondary circuit is adjusted may be neutralized.

In testimony whereof I affix my signature.
65 LOUIS COHEN.
